(57) **CLAIM**

I claim the ornamental design for a barbecue stove, as shown and described.

DESCRIPTION

FIG. 1 is a front-right-top perspective view of a barbecue stove, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof in an open position with the broken lines not forming a part of the invention.

1 Claim, 6 Drawing Sheets

FIG. 1
